HARRY SWINGLEHURST, OF BOSTON, MASSACHUSETTS, ASSIGNOR TO SCOTT & WILLIAMS, INCORPORATED, OF CAMDEN, NEW JERSEY, A CORPORATION OF NEW JERSEY.

CIRCULAR-KNITTING MACHINE.

1,087,698.

Specification of Letters Patent.

Patented Feb. 17, 1914.

Application filed May 18, 1911. Serial No. 628,055.

To all whom it may concern:

Be it known that I, HARRY SWINGLEHURST, a citizen of the United States, residing in Boston, Massachusetts, have invented certain Improvements in Circular-Knitting Machines, of which the following is a specification.

My invention relates to that class of circular knitting machines in which the needle cylinder rotates and the cam cylinder is relatively stationary, the object of my invention being to provide for the necessary lead of the yarn guide over the stitch cam when the machine is reciprocating while knitting to-and-fro, as, for instance, in producing the heel and toe pockets upon a tubular stocking web.

In the accompanying drawings:—Figure 1 is a view, partly in vertical section and partly in side elevation, illustrating the application of my invention to a circular knitting machine of the general type of that shown in the patent of George D. Mayo, No. 726,178, dated April 21, 1903, but having a rotary needle cylinder and relatively stationary cam ring instead of the reverse construction adopted in the machine of said Mayo patent; Fig. 2 is a top or plan view of certain of the elements shown in Fig. 1; Fig. 3 is a view, partly in side elevation and partly in section, of certain other of the elements shown in Fig. 1; Fig. 4 is a view similar to Fig. 3 but showing certain parts in a different position; Fig. 5 is a view showing the relation of the yarn guide to the stitch cam of the machine when the needle cylinder is moving in one direction; Fig. 6 is a similar view showing the relation of the yarn guide to the stitch cam when the machine is moving in the opposite direction; Fig. 7 is a view showing certain of the elements of the machine in a different relation to one another from that illustrated in Fig. 2; Fig. 8 is a view of part of the machine on a larger scale than Fig. 1, and illustrating a modification of the invention, and Fig. 9 is a top or plan view of certain of the elements illustrated in Fig. 8.

A machine having a rotary needle cylinder and stationary cam ring is preferable to one having the reverse arrangement of these parts, first, because higher speeds are attainable for the reason that less mass is in motion during the knitting operation, and secondly, because, in multiple feed machines,

or where yarn changers or splicers are employed and where a number of bobbins are used, these bobbins can occupy a stationary position instead of revolving about the axis of the machine as they must when the needle cylinder is stationary and the cam ring is caused to rotate or reciprocate.

In the drawings, 1 represents the bed plate of the machine in which is mounted a gear ring 2, actuated by the ordinary driving mechanism of the machine so that either rotating or reciprocating motion may be imparted thereto, depending upon whether the machine is knitting round-and-round or to-and-fro. Upon this gear ring is mounted a needle cylinder 3, surrounded by a skeleton cylinder 4, which is secured to the gear ring 2, as for instance, by means of screws or other fastenings, so that it always preserves the same circumferential relation to the needle cylinder. Vertical adjustment of the needle cylinder 3 is effected by means of pins 3^a which pass freely through holes in the gear ring and are interposed between the bottom of the needle cylinder and a ring 3^b which rests on the top of a cylinder 3^c which is susceptible of vertical adjustment by means similar to those employed in the Mayo machine, before referred to, for effecting vertical adjustment of the needle cylinder. The gear ring 2 is provided with a key, as at 5, which engages with a slot in the cylinder so as to be in driving connection with the latter. The cam ring 6 is mounted upon a fixed ring 7 on the bed 1 so as to be free to turn thereon.

Machines of the Mayo type employ but a single stitch cam, or if the machine is a multi-feed machine it will have but a single stitch cam for each yarn feed. In machines of this type it is necessary, in order to keep the yarn supplying guide always in the lead of said stitch cam, that a certain relative position be maintained between said guide and cam during the knitting operation, consequently when the machine is reciprocating for the performance of to-and-fro knitting the stitch cam must change its relation to the yarn feed on each change in the direction of movement of the machine, in order that said yarn feed may always be in the lead of the cam. When, as in the Mayo machine, the cam ring is the moving element, this can readily be effected by providing a certain amount of lost motion between the

driving gear ring and the cam ring, whereby, on each change in the direction of motion of said driving gear ring, the cam ring will remain stationary until the yarn guide, (which, in this case, moves with the driving gear ring), has secured the proper lead upon the stitch cam, but when the machine has a rotating or reciprocating cylinder and the cam ring is normally stationary this method of operation is not available. I have therefore devised means whereby, in the latter type of machine, movement can be imparted to the cam ring on each change in the direction of motion of the needle cylinder, the stitch cam being thereby shifted in relation to the yarn guide (which, in this case, is stationary) so as to preserve the proper lead of said yarn guide over the stitch cam at all times during the knitting operation.

By preference, the cam ring should be positively moved to any desired extent on each change in the direction of movement of the needle cylinder and its drive wheel, and I have therefore provided means for this purpose as shown in Figs. 1, 2, 3, 4 and 7 of the drawings, in which 144 represents the shaft carrying the quadrant whereby back and forth movements are transmitted to the driving shaft of the machine, 142 the connecting rod whereby rocking movement is imparted to said quadrant from a rotating drive wheel and 92 a shaft which controls the operation of the reinforcing mechanism of the yarn supply of the machine, and to which a rocking motion about its vertical axis is imparted whenever the machine changes from rotary to to-and-fro knitting or vice versa, these parts having similar numbers to those applied to the corresponding parts as shown in the Mayo patent above referred to, and operating in the same manner as the corresponding parts in the machine of said patent. Upon the shaft 144 are mounted so as to be free to swing two levers 9 and 10, the lever 10 being connected by a link 11 to the connecting rod 142, whereby the latter, which is constantly acting to impart rocking movement to the toothed quadrant of the machine, also imparts constant rocking movement to the lever 10. The hub of the lever 10 is slotted for the reception of a key 13 carried by a pin 14 which is free to slide longitudinally in a bored out portion of the end of the shaft 144, the latter also receiving a coiled spring 14^a which acts upon a shoulder on the pin 14 so as to constantly tend to project the same. The lever 9 has a bushing which is free to turn on the hub of the lever 10, and the hub of said lever 9 is provided with slots 13^a for the reception of the key 13 when the latter has been moved into line with said slots and then moved inward, as shown in Fig. 4, the key being free from the slots, however, when moved outward, as shown in Fig. 3, the position of the key therefore determining whether the lever 9 is clutched to the lever 10 or is free from operative connection therewith. The end portion of the shaft 144 is also slotted, as shown at 13^b in Fig. 1, the slots in said shaft and in the bushing of the lever 9 being of such width as to permit free play of the key 13 therein. A washer 15 secured to the end of the shaft 144 serves to retain all of the parts in proper position upon the latter. The shaft 92 is provided, at a point in line with the pin 14, with a projecting pin 17, and when the machine is knitting round-and-round, said shaft 92 occupies the position shown in Fig. 3, the pin 17 being then at right angles to the pin 14 and free from contact therewith, so as to permit the spring 14^a to project said pin 14 to its full extent. When, however, the parts are operated so as to change the machine from round-and-round to to-and-fro knitting, rocking movement is imparted to the shaft 92 and the pin 17 is swung around so as to strike the end of the pin 14 and move the same inwardly, as shown in Fig. 4, this action taking place at a time when the key 13 is in line with the slots in the hub of the lever 9 so as to cause said key to enter said slots, thereby clutching the lever 9 to the lever 10, and causing the two levers to reciprocate together. At the outer end of the lever 9 is a cam 19 which engages an anti-friction roller 21 or other suitable member on an arm 22, which is secured to an upright shaft 23 journaled in a bracket 24, the latter being fixedly secured to one of the fixed members of the machine frame, for instance to the member *a* of the same. At the upper end of the shaft 23 is an arm 25, which is connected by a link 26 to the flange of the cam ring 6, as shown in Fig. 2. When the machine is knitting round-and-round the parts occupy such relations to one another that the stitch cam of the cam ring 6 occupies the proper position in the rear of the yarn guide *x*. The needles may for instance, at this time, be traveling in the direction of the arrow shown in Fig. 6. As soon as the machine changes, however, from round-and-round to to-and-fro knitting, the first effect of this change of movement will be to cause the cam ring to move with the needle cylinder until the stitch cam occupies a position at the other side of the yarn guide *x*, as shown in Fig. 5, the needles then continuing to move past the cam in the direction of the arrow shown in the latter figure, and when the direction of movement of the machine is again changed, either for the production of the second course of to-and-fro knitting or for changing from to-and-fro knitting back to round-and-round knitting, a reverse movement of the stitch cam will be effected until said

cam again bears the relation to the yarn guide α shown in Fig. 6 and the needles will again move past the cam in the direction of the arrow shown in said figure. The cam 5 19 has, at each end of the inclined or acting portion 30 of the same, a straight portion 31 and when the cam is in one of its extreme positions, as shown in Fig. 2, the anti-friction roller 21 of the arm 22 occupies one of these straight portions of the groove, and 10 when the cam is in its other extreme position the anti-friction roller occupies the other straight portion of the groove, as shown in Fig. 7, so that in either of the 15 extreme positions of the cam the arm 25 and consequently the cam ring 6 is locked against accidental movement, the cam ring being therefore held in the locked position during the entire time that knitting is being performed, whether said knitting be 20 round-and-round knitting or to-and-fro knitting.

In the modification of my invention shown in Figs. 8 and 9 the base flange of the cam ring 6 instead of being supported by a fixed ring 7 on the bed plate as in the machine shown in Fig. 1, rests directly upon the top of the drive ring 2 and therefore tends constantly to partake of the movements of said 25 drive ring. On the cam ring 6, however, are a pair of separated lugs 32 provided with set screws 33, and on a fixed post 34 of the machine is a projecting arm 35 whose inner end is in position to contact with the set 30 screws 33. On each change in the direction of movement of the drive ring 2, therefore, the cam ring 6 will be caused to move therewith until such movement is arrested by contact of one or other of the set screws 33 with the fixed arm 35, this movement being just 35 sufficient to properly shift the stitch cam in respect to the fixed yarn guide, so as to give the latter proper lead on the cam when either reciprocating or to-and-fro knitting is being effected.

The construction shown in Figs. 1 to 4 is preferable to the modifications shown in Figs. 8 and 9 for the reason that it provides a positive movement of the cam ring instead of one dependent upon frictional contact of the cam ring with the drive ring and thereby relieve the drive ring from the downward pressure due to the contact of the needles with the cam. Said construction 50 also obviates the shock or jar which necessarily follows contact of either of the set screws 33 with the fixed stop 35.

I claim:

1. In a knitting machine the combination 55 of a needle cylinder, means to rotate said cylinder, means to oscillate said cylinder, a fixed yarn guide, a cam ring carrying knitting cams for the needles, means to move the cam ring with respect to the yarn guide in the direction of movement of said needle
2. In a knitting machine, the combination 60 of a needle cylinder, means to rotate said cylinder, means to oscillate said cylinder, a fixed yarn guide, a cam ring having knitting cams for the needles, and means to move said cam ring through a fixed arc, in time with the oscillations of the needle cylinder, at a rate and to an extent independent of the movements of said needle cylinder.
3. The combination, in a knitting machine susceptible of both round-and-round and to-and-fro knitting, of a moving needle cylinder, a fixed yarn guide, and a knitting cam ring which during knitting bears a fixed relation to the yarn guide, with an operating cam for said knitting cam ring, means for moving the same on each change in the direction of movement of the needle cylinder, and means acted upon by said operating cam and connected to the knitting cam ring whereby positive movement to a limited extent is imparted to the latter on each change in the direction of movement of the needle cylinder.
4. The combination, in a knitting machine susceptible of both round-and-round and to-and-fro knitting, of a moving needle cylinder, a fixed yarn guide, and a knitting cam ring which during knitting bears a fixed relation to the yarn guide, with an operating cam for said knitting cam ring, means for moving the same on each change in the direction of movement of the needle cylinder, and means acted upon by said operating cam and connected to the knitting cam ring whereby positive movement to a limited extent is imparted to the latter on each change in the direction of movement of the needle cylinder, said operating cam having an acting member and locking members at each end of the same, whereby the knitting cam ring will be locked in position when at rest.
5. The combination, in a knitting machine susceptible of both round-and-round and to-and-fro knitting, of a moving needle cylinder, a fixed yarn guide, and a cam ring which during knitting bears a fixed relation to the yarn guide, with an operating cam for said knitting cam ring and intervening mechanism whereby said operating cam is caused to effect positive movement to a limited extent of the cam ring whenever there is any change in the direction of movement of the needle cylinder, a lever carrying said operating cam, another lever having connection with a member of the needle-cylinder-reciprocating mechanism, whereby rocking movement is imparted to said lever, and mechanism for clutching said cam-carrying lever to said rocking lever or releasing it therefrom.
6. The combination, in a knitting machine susceptible of both round-and-round and to-and-fro knitting, of a moving needle cylinder

cylinder, and means to hold the cam ring fixed in its adjusted position.

2. In a knitting machine, the combination 70 of a needle cylinder, means to rotate and oscillate said cylinder, a fixed yarn guide, a cam ring having knitting cams for the needles, and means to move said cam ring through a fixed arc, in time with the oscillations of the needle cylinder, at a rate and to an extent independent of the movements of 75 said needle cylinder.

3. The combination, in a knitting machine susceptible of both round-and-round and to-and-fro knitting, of a moving needle cylinder, a fixed yarn guide, and a knitting cam ring 80 which during knitting bears a fixed relation to the yarn guide, with an operating cam for said knitting cam ring, means for moving the same on each change in the direction of movement of the needle cylinder, and means acted upon by said operating cam and connected to the knitting cam ring whereby positive movement to a limited extent is imparted to the latter on each change in the direction of movement of the needle cylinder.

4. The combination, in a knitting machine 90

susceptible of both round-and-round and to-and-fro knitting, of a moving needle cylinder, a fixed yarn guide, and a knitting cam ring which during knitting bears a fixed relation to the yarn guide, with an operating cam for said knitting cam ring, means for moving the same on each change in the direction of movement of the needle cylinder, and means acted upon by said operating cam and connected to the knitting cam ring whereby positive movement to a limited extent is imparted to the latter on each change in the direction of movement of the needle cylinder, said operating cam having an acting member and locking members at each end of the same, whereby the knitting cam ring will be locked in position when at rest.

5. The combination, in a knitting machine 100 susceptible of both round-and-round and to-and-fro knitting, of a moving needle cylinder, a fixed yarn guide, and a cam ring which during knitting bears a fixed relation to the yarn guide, with an operating cam for said knitting cam ring and intervening 110 mechanism whereby said operating cam is caused to effect positive movement to a limited extent of the cam ring whenever there is any change in the direction of movement of the needle cylinder, a lever carrying said operating cam, another lever having connection with a member of the needle-cylinder-

reciprocating mechanism, whereby rocking movement is imparted to said lever, and mechanism for clutching said cam-carrying 120 lever to said rocking lever or releasing it therefrom.

6. The combination, in a knitting machine 130 susceptible of both round-and-round and to-and-fro knitting, of a moving needle cylinder

der, a fixed yarn guide, and a knitting cam ring which during knitting bears a fixed relation to the yarn guide, with an operating cam for said knitting cam ring and intervening mechanism whereby said operating cam is caused to effect positive movement to a limited extent of the knitting cam ring whenever there is any change in the direction of movement of the needle cylinder, a lever carrying said operating cam, another lever having connection with a member of the needle-cylinder-reciprocating mechanism whereby rocking movement is imparted to said lever, mechanism for clutching said cam-carrying lever to said rocking lever or releasing it therefrom, a shaft forming an element of the yarn reinforcing mechanism of the machine, and means whereby the operation of said shaft is caused to effect operation of the clutch.

7. The combination, in a knitting machine susceptible of both round-and-round and to-and-fro knitting, of a moving needle cylinder, a fixed yarn guide, and a knitting cam ring which during knitting bears a fixed relation to the yarn guide, with an operating cam for said knitting cam ring and intervening mechanism whereby said operating cam is caused to effect positive movement to a limited extent of the knitting cam ring of the machine on each change in the direction of movement of the needle cylinder, a lever carrying said operating cam, another lever having connection with a member of the mechanism for imparting reciprocating

movement to the needle cylinder, whereby rocking movement is imparted to said second lever, a clutch member for locking together said cam lever and rocking lever, a shaft having rocking movement imparted thereto when the machine changes from round-and-round to to-and-fro knitting or from to-and-fro knitting to round-and-round knitting, and a projection on said shaft acting upon the clutch member to cause the same to move into locking position.

8. The combination, in a knitting machine susceptible of both round-and-round and to-and-fro knitting, of a moving needle cylinder, a fixed yarn guide, and a cam ring which during knitting bears a fixed relation to the yarn guide, with a fixed support for said cam ring and a connection between said cam ring and a moving member of the machine, which shifts its position on each change in the direction of the movement of the needle cylinder, whereby the cam ring will be positively moved on each such change and the stitch cam will be shifted in respect to the yarn guide so as to cause the latter to preserve its proper lead over the cam during the knitting operation.

In testimony whereof, I have signed my name to this specification, in the presence of two subscribing witnesses.
